UNITED STATES PATENT OFFICE.

ERNEST STEAD, OF BINGHAMTON, NEW YORK.

LENS-GRINDING MACHINE.

1,202,285.

Specification of Letters Patent. Patented Oct. 24, 1916.

Application filed March 18, 1915. Serial No. 14,757.

To all whom it may concern:

Be it known that I, ERNEST STEAD, a citizen of the United States, and resident of Binghamton, in the county of Broome, in the State of New York, have invented new and useful Improvements in Lens-Grinding Machines; of which the following, taken in connection with the accompanying drawings, is a full, clear, and exact description.

10 This invention relates to certain improvements in tool-holders for lens-surface grinding machines, the object being to provide a simple and comparatively inexpensive tool holder which may be used in connection with various forms of grinding tools or grinding machines.

Another object is to provide means whereby the tool may be more conveniently and accurately adjusted to the work or mechanism carrying the object to be operated upon.

Other objects and uses relating to specific parts of the device will be brought out in the following description.

25 In the drawings Figure 1 is a top plan of a device for supporting a pair of grinding tools. Fig. 2 is a transverse vertical sectional view of the same device taken on line 2-2, Fig. 1. Fig. 3 is a sectional view of 30 one of the tool holders as used for receiving and supporting one of the standard forms of tools. Fig. 4 is a sectional view of the same tool holder shown in Fig. 3 with the end section of the inner telescoping member in operative position for receiving and supporting a different standard type of tool. Fig. 5 is a horizontal sectional view through the tool holder in the plane of the guide pins for the sliding clamp. Figs. 6 and 7 35 are detail perspective views of the inner telescoping member of the tool holder and disk. Figs. 8, 9, 10, 11 and 12 are perspective views of different standard forms of grinding tools, all adapted to be used with 40 my improved tool holder. Fig. 13 is a perspective view of a portion of a lens-grinding and polishing machine showing the manner of mounting my improved tool holder thereon.

50 In order that the utility and range of use of my invention may be clearly understood, I have shown a portion of the frame of a standard form of lens grinding machine now in common use for grinding a plurality 55 of, in this instance two, lenses at the same time and consisting of a horizontal shelf

—A— having a rib or bead —a— running along its front edge for receiving and supporting a tiltable bracket —1— having hook shape or grooved flanges —2— resting upon the upper edge of the rib —a— with sufficient clearance at the front and rear sides of the rib to allow a limited forward and rearward tilting movement of said bracket. This bracket is provided near its ends with 60 upstanding ears or lugs —3— having vertically elongated slots —4— for receiving pivotal clamping screws —5— and permitting a limited vertical adjustment thereof, each clamping screw being engaged in a 65 threaded aperture of a crank arm —6— on one end of a horizontal shaft or spindle —7—, extending transversely of and above the shelf —A—, as shown more clearly in 70 Figs. 1 and 4.

75 The central portion of the bracket —1— is provided with rearwardly projecting ears or lugs —8— and —9— spaced a sufficient distance apart to receive between them the shelf —A—, as shown in Fig. 2, said ears 80 or lugs being extended some distance rearwardly beyond the rib —a— and provided with threaded apertures —10— and —11— at different distances from the base of the lugs for receiving adjusting screws —12— 85 and —12'— by which the bracket may be adjusted upon the rib —a— to different angles relatively to the shelf —A— and clamped in its adjusted position.

90 Each screw —5— serves as a pivot about which the crank arm —6— may be adjusted to vary the position of the shaft or spindle —7— and tool-holder laterally and vertically, while the adjustment of the clamping screw —5— in the slot —4— serves also to 95 permit vertical adjustment of said shaft or spindle.

An upright cylindrical tool holder —13— is mounted upon the spindle —7— and adapted to be adjusted about the axis thereof and also lengthwise of said axis, and for this purpose is provided in its lower end with a diametrically extending journal opening —14— in which the spindle —7— is fitted, said tool holder being provided 100 with a radial set screw —15— for engaging the periphery of the spindle —7— to retain the tool holder in its adjusted position, the portion of the spindle engaged by the set screw being slightly reduced in diameter 105 so that any burs which may be formed thereon by the set screw will not prevent the 110

free withdrawal or turning movement of the tool holder from or upon the spindle when such withdrawal or turning movement is desirable, said reduced portion being elongated axially to allow the lengthwise adjustment of the tool-holder previously referred to.

The axes of the pivotal screws —5— and spindle —7— are parallel and spaced some distance apart, and together with the other adjustments previously described permit the tool-holder with the tool thereon to be accurately and expeditiously adjusted to the work which is moved in a manner well-known to those skilled in this art, and not necessary to herein illustrate or describe for the reason that the work-holder and its operating means form no part of my present invention.

20 The major portion of the tool holder —13— above the spindle —7— is tubular to form a cylindrical socket —16— open at the top and slightly enlarged near its upper end to form an annular shoulder —17— for receiving and supporting a cylindrical section or bushing —18— which telescopes within the holder —13— and is provided at its upper end with an annular flange —19— normally resting upon the shoulder —17— to limit the inward movement of the section —18—. This bushing —18— constitutes a separable section of the tool holder 13, and while it is closely fitted within said tool holder —13— to turn freely therein for properly adjusting the grinding tool resting thereon, it is held in its adjusted position by one or more set screws —20— engaging in threaded apertures in the adjacent sides of the tool-holder —13—, as shown in Fig. 3.

40 The upper face of the section 18 is disposed in a substantially flat plane at right angles to the axis of the holder, said section being provided with a central vertical opening —21— therethrough, preferably rectangular in cross section, for receiving a radially sliding clamping member —22— which is secured to guide pins —23— moving in parallel guide-openings —24—, as shown in Figs. 3, 4 and 5.

50 The thickness of the clamping plate —22— is considerably less than the corresponding width of the opening which extends to one side of the center of the bushing a greater distance than at the opposite side corresponding to the thickness of the plate —22— so that this plate may be moved into the extension to leave a clear central opening of substantially the same cross sectional area as the boss —b— of a grinding tool —B—, shown in Figs. 1, 4 and 10, in which case the bushing section —18— is provided with a supplemental disk section —18'— having its lower and upper faces substantially flat and parallel to rest flatwise upon the upper face of the

section —18— and also to form a flat supporting face for the grinding tool —B—, the section —18'— being provided with a central opening —21'— registering with the opening —21— except that the portion of the opening which extends the greatest distance beyond the center or axis of the holder is reduced in width, as shown in Fig. 7, to receive a correspondingly reduced gripping portion —22'— on the upper edge of the clamping plate —22—, as shown in Figs. 3 and 6. This clamping plate —22— is utilized in securing another form of grinding tool as —C—, Figs. 3 and 8, directly to the upper face of the bushing section —18—, and for this purpose the central portion of the under side of the grinding tool —C— is provided with a recess or transverse groove —c— forming opposite shoulders —c'— which are slightly undercut or dove-tailed, while the reduced gripping portion —22'— on the upper edge of the clamping member —22— extends into the recess —c— and is also slightly undercut or dovetailed along its gripping face for interlocking engagement with the adjacent shoulder —c'— of the grinding tool —C—, it being understood that when the clamping member —22— is adjusted for securing the grinding tool —C— in place, its reduced gripping portion —22'— projects sufficiently above the upper face of the bushing section —18— to enter the recess —c—.

The clamping plate —22— is forced into gripping engagement with the grinding tool —C— by means of a screw —25— engaged in a radially threaded aperture in the bushing section —18— and provided with a tapered inner end for wedging engagement with the face of the plate —22— opposite that which engages the grinding tool —C—, as shown in Figs. 3 and 5.

The bushing —18— and grinding tool —C— are provided with co-operative means for centering the grinding member upon the bushing consisting, in this instance, of studs —26— on the upper face of the bushing entering apertures —27— in the lower face of the grinding tool, this centering means also serving as a part of the locking means for holding the grinding member on the bushing for the reason that when the clamping member —22— is tightened by the screw —25—, the grinding tool is firmly pressed against the studs —26— to resist the pressure produced by the tightening of the clamping plate.

When the holder is used to support the type of grinding tool —B—, shown in Figs. 1, 4 and 10, said holder is held in place by a set screw —28— which is engaged in a threaded aperture in the bushing and engages the adjacent side of the boss —b—, as shown in Fig. 4, the supplemental disk section —18'— being provided with apertures

—29— for receiving the studs —27— and coöperating therewith to center the disk on the bushing section —18—. If, however, it is necessary to use the type of grinding tool 5 —C—, shown in Figs. 3 and 8, it is simply necessary to remove the tool —B— and plate —18'— and to replace the plate —18'— with the tool —C—, or if it is desired to use either 10 of the types of grinding tools —D—, Fig. 9, and —E—, Fig. 11, it is only necessary to remove the bushing section —18—, thus permitting either of the sections —D— or —E— to be inserted into the upper end of the socket —16—, either side up, each of 15 those grinding tools being provided with an annular rib —d— and —e—, respectively, adapted to rest upon the shoulder —17—, after which the particular grinding tool which may be used may be clamped in place 20 by the same set screw which is used to clamp the bushing —18— in place. In like manner, either of the grinding tools —D— or —E— may be substituted by another standard form 25 of grinding tool, as F, shown in Fig. 12, and which is separably attached to a suitable base portion —f— adapted to rest upon the bottom of the socket —16—, leaving the 30 grinding tool —F— projecting in a plane above the upper end of the tool holder —13—.

The grinding tools shown in Figs. 8 to 12, inclusive, are standard types and it will be seen from the foregoing description that the tool holder may be used for supporting any 35 one of these tools and that the various adjustments provided therefor permit the grinding tool to be easily adjusted to the work to secure the greatest degree of accuracy in grinding, but I do not wish to 40 limit myself to the specific form of adjusting means, since it is evident that other devices may be used to effect the same result without departing from the spirit of this invention.

45 The same tool holder is adapted to be used in connection with machines having stationary or rotary vertical spindles instead of the horizontal spindle —7—, and for this purpose is provided with a central cylindrical bore —30— Fig. 3 adapted to fit upon a vertical spindle, not shown, in which case it is, of course, evident that the spindle —7— would be withdrawn, but the same set screw —15— which serves to tighten the 50 holder —13— upon the spindle —7— may also serve to secure it to the vertical spindle or shaft.

In Fig. 13 is shown a portion of a lens-grinding machine adapted for grinding a 55 plurality of, in this instance two, lenses at a time comprising a main supporting frame —40— carrying the shelf —A— upon which the tiltable bracket —1— carrying the arms —6— to which the spindles —7— are secured 60 for carrying the tool-holders —13— forming

the subject-matter of my present invention, previously described.

Coöperating with the tool holders are suitable lens-holders —41— adapted to be operated in any suitable manner not necessary 70 to herein illustrate or describe for the reason that the lens-holder and its operating means form no part of my present invention, the machine illustrated being of the standard type, known to the trade as the hercules 75 grinder, now in common use and manufactured by The Standard Optical Company of Geneva, N. Y.

What I claim is:

1. A tool-holder for lens-grinding or polishing tools, said holder having means for attachment to either a vertical or horizontal support with its tool-receiving side facing in the same direction.

2. In combination with a lens grinding or 85 polishing tool, a holder therefor, and means for adjusting the holder about separate parallel axes spaced some distance apart.

3. A tool-holder for lens-grinding or polishing tools, said holder having openings at 90 right angles to each other for receiving either a vertical or a horizontal support with its tool-receiving side facing in the same direction.

4. In combination with a lens grinding 95 tool, a holder therefor, a support upon which the holder is journaled for rotary adjustment about an axis at right angles to that of the holder, and means for clamping the tool holder to said support, said support 100 being adjustable rotarily about a different axis, and separate clamping means for the support.

5. A tool-holder for lens-grinding or polishing tools, said holder having openings at 105 right angles to each other for receiving either a vertical or a horizontal support with its tool-receiving side facing in the same direction, and a clamping device on the holder movable transversely of both 110 openings for retaining the holder on either support.

6. In a lens grinding machine, a holder for a grinding tool, a journal bearing therefor at right angles to its axis and upon which 115 the tool holder is adjustable rotarily and lengthwise, means for clamping the tool holder to said bearing, and a rocking support for the journal bearing.

7. In a lens grinding machine, the combination with a main-supporting frame, a bracket tiltably mounted on said frame for adjustment to different angles, means for holding the bracket in its adjusted position, a rocking member mounted on the bracket 120 to swing in a plane at right angles to the plane of adjustment of the bracket and provided with a journal bearing some distance to one side of its axis of rocking movement, means for clamping the rocking member in 125 130

- its adjusted position, a holder for a grinding tool journaled on said bearing, and means for clamping the tool holder to the journal bearing.
5. In a lens grinding machine, a holder for a grinding tool, a journal bearing for said holder to permit the latter to be adjusted rotarily thereon, means for clamping the holder in its adjusted position upon the journal bearing, and separate means for 10 rocking the journal bearing and holder thereon in different planes at right angles to each other including separate devices for holding the journal bearing and tool holder 15 in their adjusted positions.
9. In a lens grinding machine, a grinding tool and a holder therefor comprising telescoping members having co-operative means for limiting their sliding movement one upon the other in one direction, additional means for clamping said members against relative movement, the grinding tool and one of the members having co-operative 20 means for centering the grinding tool relatively thereto, a clamping member slidable radially on the tool-supporting member for 25 engaging a portion of the grinding tool, and means for tightening and releasing the clamping member against and from the 30 grinding tool.
10. In a lens grinding machine, a tool holder having means for centering a grinding tool thereon and provided with a central opening, a clamping plate slidable in said opening for engaging a grinding tool, and means for adjusting said plate to clamp the tool.
11. In a tool grinding machine, a lens holder comprising separable telescoping members having co-operative means for limiting their axial movement one upon the other in one direction, the inner member being provided with means for centering and clamping a 40 grinding tool thereto.
12. In a lens grinding machine, a tool 45 holder comprising separable telescoping members having co-operative means for limiting their relative axial movement in one direction, the inner member being provided with means for centering and clamping a 50 grinding tool thereto, said means including a sliding clamping plate and a screw for adjusting the same.

In witness whereof I have hereunto set my hand this 11th day of March, 1915.

ERNEST STEAD.
